UNITED STATES PATENT OFFICE.

ANN M. FREEMAN, OF KANSAS CITY, MISSOURI

DRESS-CUTTING RULE.

SPECIFICATION forming part of Letters Patent No. 317,332, dated May 5, 1885.

Application filed September 13, 1884. (No model.)

To all whom it may concern:

Be it known that I, ANN M. FREEMAN, a citizen of the United States, residing at Kansas City, in the county of Jackson and State of Missouri, have invented certain new and useful Improvements in Dress-Cutting Rules; and I do declare the following to be a full, clear, and exact description of the invention, such as will enable others skilled in the art to which it appertains to make and use the same, reference being had to the accompanying drawing, and to letters or figures of reference marked thereon, which form a part of this specification.

15 The drawing is a representation of this invention, and is a plan view of the pattern.

This invention has relation to dress-makers' guides or pattern-rules; and it has for its object to provide a guide-pattern which will facilitate cutting the outer and inner parts of a sleeve.

In the accompanying drawing, the letter A designates the guide-pattern, which may be made of stout paper or stiffened cloth. B 25 represents its arched upper edge, which serves as the guide in cutting the shoulder. This arched edge B is made sufficiently curved to serve for the highest shoulder. Within this edge guide-lines b and b', of less curvature, are provided with perforations, as shown at c, to enable the cutter to place guide-marks on the cloth for lower shoulders.

From the rear portion of the shoulder-guide extends downward the guide-strip D, the back 35 edge, E, of which forms the guide for cutting the outer edge of the outer sleeve-section, or that edge which joins the inner sleeve-section to form the outer seam. The guide-edge E also serves in cutting the outer edge of the inner sleeve-section.

Near the guide-edge E are marked the guide-lines e and e', which are sweeping curves extending from the back point of the shoulder-guide downward, and gradually merging into 45 the guide-edge E a little below the elbow. These lines are provided with perforations e, to enable the cutter to place the guide-marks on the cloth in preparing to cut sleeves of less than the largest size. The front edge, F, of the

strip D extends vertically downward from the 50 arched piece G, which forms the shoulder-guide, and from the inner end of the curved under margin, H, thereof, which extends from the front point of the shoulder upward and inward to said end, which is indicated at d, 55 and which is even with the back point d' of the shoulder-guide. The front edge of the strip D is marked with a scale, N, of inches and parts of an inch, as shown, and serves for the purposes of measurement. The convex 60 under margin, H, is the guide for cutting the top of the inner sleeve-section.

The length of the sleeve having been measured, and the tops and backs of the sleeve-sections cut according to the pattern-guide, 65 the front edges are cut in a sweeping curve by the eye, allowing for adults four and one-half inches difference between the back edges which are joined to form the outer seam, and the front edges which, when connected, form 70 the inner seam. The sleeve is cut from a square of cloth formed in accordance with the size of the bust. This square of cloth has an elbow-line marked or creased on it, dividing the sleeve with reference to its length. 75

To cut the sleeve, proceed as follows: Place the pattern right side up with the * (star) at a distance of one and a half inch from the edge of goods, and on the elbow-line marked on the goods, for inside seam of upper arm. 80 To cut the inside seam of lower arm, the pattern is turned wrong side out and upside down, and the * (star) of the strip placed on the elbow-line of goods, which will give the proper curve, cut as long as required. The outer 85 seam of upper arm is cut according to the outer upper edge of the pattern. The outer seam of lower arm is simply a continuation of the line already started when cutting the upper arm, which gives a tapering form to the 90 lower part of the sleeve. This seam is cut down straight until the required length is obtained.

Having described this invention, what I claim, and desire to secure by Letters Patent, 95 is—

A dress-maker's sleeve-pattern guide for cutting sleeve-sections, consisting of the long

strip D, having the straight graduated front measuring-edge and the curved rear guide-edge, E, and at the top of said strip the arched piece G, having the arched upper guide-edge, 5 B, and the convex under guide-edge, H, respectively designed for cutting the tops of the outer and inner sleeve-sections, substantially as specified.

In testimony whereof I affix my signature in presence of two witnesses.

ANN M. FREEMAN.
